GRIP AND CONTROL MECHANISM FOR
BOWLING

Albert A. Zander, Detroit, Mich.

Application December 2, 1947, Serial No. 789,182

13 Claims. (Cl. 3-12)

1

This invention relates to article gripping attachments for use with artificial arms and the like and is more particularly directed to such an attachment for handling bowling balls.

Various devices have heretofore been suggested for assisting handicapped persons to participate in gainful employment by providing substitutes for hands or feet capable of performing to a limited extent the normal functions of these body members. Some of these substitutes have taken the form of hooks held in an artificial arm.

More recently attention has been directed to finding ways of making recreational activities available to handicapped persons, especially to war veterans.

The present invention is also thus intended and has as its principal object the provision of an attachment for artificial arms which will enable a person having the same to participate in the game of bowling with substantially the same skill as a person having no handicap.

A further object is the provision of mechanism attachable to an artificial arm and capable of releasably gripping a bowling ball or other object under control of the user and of releasing the same at the will of the user.

A specific object is to provide an attachment for artificial arms that includes means for releasably gripping a bowling ball without danger of its accidental self-release and means for controlling the gripping means in such manner that the ball may be released at the will of the player, for instance, at a predetermined portion of the forward swing corresponding to that at which a skilled player will normally cast the ball down the alley.

Another object is to provide a bowling attachment having a grip which must be released incidental to insertion in the socket of the ball and which is self-locking when in gripping position.

An additional object is to provide a bowling attachment for artificial arms which is operable to securely grip the bowling ball and from which the ball may be instantly released under control of the player during forward swinging movement of the ball, the ball camming itself free of the grip incidental to said release and movement.

Still another object is to provide a balanced bowling ball having a single socket that is of greater cross-section inwardly of the surface of the ball than at the periphery of the ball.

Other objects and advantages of my invention will become more apparent from the following description taken in connection with the accompanying drawings wherein:

2

Figure 1 is a view in perspective of a player using my invention and in position about to release the ball;

Figure 2 is an enlarged view of the ball of my invention seen in Figure 1 and showing the manner in which the attachment of my invention grips the ball;

Figure 3 is an assembled view of the attachment of my invention showing the jaws thereof locked in gripping position; and

Figure 4 is an exploded view in perspective showing the parts included in the attachment of my invention.

Referring to the drawings in which similar numerals refer to similar parts throughout the several views, 10 represents an artificial arm or other body member. Non-rotatably secured in the free end 12 of the arm is a flanged bushing 14 having a bore 16 provided with threads 18 interengaged with threaded stem 20 of one end of an elongated member or shaft generally designated by the number 22.

Preferably the shaft 22 will be adjustable in the bushing to bring the attachment to the position seen in Figure 1 and may for example be locked in such position by a lock nut 23 or by having the threads of the bushing and stem run out at such points as to cause them to wedge when drawn up tightly with the shaft and arm in the relative positions shown in Figure 1.

The opposite or free end 24 of the member 22 is provided with a ball grip 26 comprising a stationary finger or jaw 28 forming an integral part of the member 22 and a laterally movable or swingable finger or jaw 30 preferably hinged or pivoted to the member 22 on an axis 32. Thus the finger 28 may be journaled on a shaft 34 and be adapted to be oscillated relative to the finger 28.

The hub or pivoted end 35 of finger 30 is formed like a clevis, having ears 36, 38 of generally circular shape concentric with the axis 32 which straddle a generally circular shaped rectangular sectioned portion 40 of the member 22 intermediate the ends 20, 24. The stud 34 has a threaded shouldered end 42 tightly screwed and anchored in the ear 36 while the shank 46 of the stud journals in a bore 48 of the member portion 40 and in the bore 50 of the ear 38.

The fingers 28, 30 of the grip 26 when in closed (released) position together preferably have a generally cylindrical shape that tapers convergingly from the hub 35 and member 22 portion 40 and terminates in an enlarged end 51 preferably of ball-like character having an annular

camming band 52 to which further reference will hereinafter be made and which provides the camming faces 53, 54, 55 and 56 on the fingers 28, 30 respectively. Thus the fingers 28, 30 have inner flat faces 58, 60 respectively which in abutted relationship (released) form a plane passing through the axis 32 and offset from the axis 62 of the threaded end 20, and have transverse sections of semi-circular shape.

It will be noted that a plane passing through the axis of the fingers 28, 30 and paralleling the face 64 (Figure 4) of the portion 40 of the member 22 will pass through the axis of the portion 20 of the member 22 and of the arm 10, i. e. they are co-axial in a plane parallel to the face of the drawing.

Pivotedly mounted on the portion 40 of the member 22 is a finger latch generally designated by the numeral 66 whose function is to releasably hold or lock the finger 30 in the spread apart position relative to the finger 28 seen in Figure 3 as when gripping the ball 70, (see Figure 2). As seen in Figures 3 and 4 the latch is preferably L-shaped arm portions 72 and 74. The arm portion 72 is of inverted U section having downwardly directed legs 76 which include ears 78 that straddle the upper edge 80 of the portion 40 of the member 22. The latch is secured to the member 22 by a stud or shaft 82. The stud has a threaded shouldered portion 84 tightly screwed and anchored in one of the ears 78 while the shank 86 of the stud journals in a bore 88 of the member 22 and bore 90 of the latch, it being noted that the axis of the stud 82 is normal to the face 64 of the member 22 in Figure 3, and on the opposite side of the longitudinal axis 62 in Figure 3 from the axis 32 of the movable finger. The legs 76 of the latch have end faces 92 lying in a plane passing through the axis of the stud 34 and normal to a plane paralleling the face 58 of the leg 28. The legs 76 are adapted to engage in notches or recesses 94 of the movable finger ears 36, 38 (Figure 4) when the fingers are spread apart; the end faces 92 of the legs being adapted to abut faces 96 of the ears 36, 38 upon any tendency of the fingers to close.

The arm 74 of the latch has a bore 98 and a slot 100 cut through the outer edge portion of the arm and opening into the bore 98.

A resilient element, for instance, a helical spring 102 is seated in opposite recesses or blind bores 104 in the faces 58, 60 of the fingers 28, 30 respectively and constantly urges the fingers 28, 30 apart into gripping position.

Similarly, a helical spring 106 is seated in opposite bores 108, 110 respectively of the member 22 and latch 66 to constantly urge the latch 66 into locking position.

It will be observed that the arm 72 of the latch 66 when in locking position has its abutment face 92 located between the axes of the studs 34, 82, and on a radial line from the center of stud 34, so that the latch will not be accidentally released by any tendency of the fingers 28, 30, to close. Stated otherwise the arm 72 of the latch will not be forced outwardly by pressure between the abutment faces 92, 96 caused by closing effort on the fingers 28, 30.

For controlling release of the latch 66 I provide a flexible cable 112 received in the slot 100 of the latch and which may apply a releasing force to the arm 74 through a ball 114 which seats in the inner end of the bore 98 of the arm 74 when tension is applied to the cable 112. The cable passes through a hole 116 in the ball and has a

knot or other enlargement 118 to prevent separation of the ball from the cable.

The cable 112 as seen in Figure 1 extends beneath the clothing of the right-handed player 120 there shown and is arranged to go up the right hand arm 122 and back of the right shoulder 124 and connect with a loop 126 hooked over or fastened to the left hand shoulder 128 of the player. Suitable guides not shown are provided wherever necessary.

It will be understood that a similar but reverse arrangement will be provided where the player is left-handed.

The ball to be used by a player having my attachment need have only a single finger hole or socket 130 which as seen in Figure 2 is arranged radially inwardly of the ball and has a small radial outer bore 132 and a larger radial inner bore 134 which in effect undercuts the bore 132 to provide an annular locking shoulder 136 for receiving the fingers 28, 30 of the grip 26. It will be understood that a plurality of pockets may be provided if desired and that the ball will be balanced by the number provided.

In operation of the attachment of my invention, the fingers 28, 30 are inserted in the socket 130 of the ball 70, the spherical camming surfaces 53, 55 at the outer ends of the fingers 28, 30 respectively, acting against the rim 138 of the bore 132 to cam the fingers together against the opposing action of the spring 102. Once the ball grips 26 get by the annular shoulder 136 of the ball socket the fingers are again forced apart by the spring 102 and their cam surfaces 52, 54 bear against this annular shoulder, as seen in Figures 2 and 3. At this time the latch 66 is able under bias of the spring 106 to automatically enter the locking slots 94 of the movable finger 30 to lock the fingers in their relative positions in the ball socket. It will be understood that the latch is first released before attempting to insert the fingers 28, 30 in the ball socket and that sufficient operating clearance will be provided between the faces 92, 96 of the latch and movable finger respectively when the grip is in position in the socket 130 to permit easy entrance of the latch arms 72 into the slots 94. Any such clearance will be taken up immediately upon lifting the ball.

The player is now ready to cast or roll the ball down the alley. He takes the normal position that any non-handicapped player would assume and takes the normal forward steps and backswing before swinging the ball forwardly by a forward swinging movement of the ball throwing arm. At the end of the latter movement the latch is released and the mass of the ball acts on the cam surfaces 54, 56 of the fingers to close the fingers together and compress the spring 102 wherefore the ball speeds on its way down the alley.

It is to be noted that in the backswing of the ball the forearm and the upper arm portions of the player's throwing arm are crooked somewhat so that no tension is applied to the cable 112. However as the player swings the ball forwardly the arm portions straighten out until they are substantially in line. During this latter portion of the swing tension is applied to the cable by the straightening or stretching of the arm alone and/or by a forward movement of the left shoulder of the player which anchors the cable or both cooperating together at the end of the forward swing to release the latch and allow the ball to

be freed. No special skill is required to obtain proper operation.

From the foregoing description it will be evident that I have presented a novel attachment for artificial arms having many uses and especially adapted to provide a means of recreational activity for handicapped persons through bowling.

The attachment is easy to use and safe. It requires no special instruction and the player need have no consciousness of being handicapped when using the same. In actual use I have attained scores of 150 and higher.

While the particular attachment herein is well adapted for carrying out the objects of my invention it will be understood that various modifications, changes and substitutions may be made without departing from the spirit thereof and the present invention is therefore to be construed to include such modifications, changes, and substitutions as may come within the scope of the following claims.

I claim:

1. A bowling apparatus for persons having an artificial arm, comprising ball carrying and gripping means secured to said arm, said gripping means being operable into gripping position relative to a bowling ball, releasable locking means operably associated with said gripping means and operable to positively lock said gripping means in ball gripping position, means operably associated with said locking means and operable by the player to release said locking means, and means on said gripping means operable to release said gripping means from gripping position relative to the ball incident to separating movement between the ball and said gripping means following release of said locking means.

2. An article gripping attachment for an artificial arm, comprising a relatively fixed member having opposite ends, one of said ends being secured in said arm, the other end having a finger for insertion in the article, a second member mounted for pivotal movement relative to said fixed member and having a finger movable to engage the article, resilient means operable between said members for biasing said movable finger into a predetermined relationship whereby the said fingers are in gripping relation to the article, means operable to releasably lock said movable finger in said predetermined relation, means for releasing the locking means, and means on said movable finger operable to release said movable finger from said gripping position incident to separating movement between said fingers and article following release of said locking means.

3. An article gripping attachment for an artificial arm, comprising a relatively fixed member having opposite ends, one of said ends being secured in said arm, the other end having a finger, a second member carried by said first member, said second member also having a finger, said fingers being insertable in the article and being movable away from each other to effect gripping of the article, means for resiliently moving said fingers away from each other, means for releasably and positively holding said fingers in separated relation, and cam means carried by at least one of said fingers for releasing said attachment from the article following release of said holding means and upon relative separating movement of the article and attachment.

4. An article gripping attachment for an artificial arm, comprising a relatively rigid member having opposite ends, one of said ends being secured in said arm, the other end having a finger,

a second member pivotally carried by said first member, said second member also having a finger, said fingers being insertable in the article and being movable away from each other to effect gripping of the article, resilient means for urging said fingers in separated relationship, latching means carried by said rigid member and engageable with said second member for releasably locking said fingers in separated relationship, resilient means biasing said latching means into locking position, and means for releasing said latching means.

5. An article gripping attachment for an artificial arm, comprising a socket secured in said arm, a relatively rigid member having opposite ends, one of said ends being secured in said socket, the other end having a finger, a second member pivotally carried by said first member and having a finger coextensive with said first mentioned finger, said fingers being insertable in the article and being movable away from each other into position to effect gripping of the article, resilient means operable between said fingers for constantly urging said fingers apart, a locking recess on said second member, a latch engageable in said recess for locking said fingers in separated relationship, resilient means for urging said latch into locking position, means operable to release said latch, and cam means on said fingers to retract said fingers from said gripping position incident to relative separating movement between said fingers and article following release of said latch whereby to facilitate release of said fingers from the article.

6. A bowling attachment for an artificial arm, comprising a relatively rigid member detachably secured to said arm and having a ball gripping jaw at its free end, a second ball gripping jaw pivotally mounted on said member, a releasable latching element for positively holding said jaws in a predetermined relation when gripping the ball, and means associated with said jaws operable following release of said latching element for moving said jaws from said predetermined position to facilitate release of said jaws from the ball.

7. A bowling attachment for an artificial arm, comprising a relatively fixed member having one end detachably secured to said arm and its opposite end presenting a ball gripping jaw, a second ball gripping jaw pivotally mounted on said member and movable relative thereto, said ball gripping jaws comprising finger-like elements of tapered semi-circular section at least one of which has an enlarged tip, spring means for urging the ends of said jaws apart, latching means operable on said movable jaw to prevent closing of said jaws, and means under control of the bowler for releasing said latch.

8. A bowling attachment for an artificial arm, comprising an elongated fixed member having one of its ends secured in said arm and having its other end provided with a pair of relatively movable fingers insertable in a bowling ball for gripping the same, one of said fingers being integral with said member and the other being pivotally mounted on said member, and resilient means constantly urging said fingers apart, said fingers having enlarged ends and there being cam surfaces on said enlarged ends operable relative to said ball for releasing said fingers.

9. A bowling attachment for an artificial arm, comprising an elongated member detachably secured to said arm and having a free end provided with a ball gripping jaw, a second jaw pivotally

mounted on said member and cooperable with said first jaw for gripping a bowling ball, resilient means biasing said jaws into gripping position, releasable latching means for holding said jaws in predetermined open position, means for releasing said latching means, and means on said jaws cooperable with the ball for releasing said fingers therefrom.

10. A bowling attachment for an artificial arm, comprising an elongated fixed member having one of its ends formed with a semi-circular tapered finger terminating in an enlarged tip and having its other end threaded into a receiving socket secured in said arm, said member also having a portion of rectangular section intermediate said ends; a second member having a clevis portion pivotally secured to said rectangular section and having a finger portion of similar shape and structure to said first mentioned finger, the said fingers being swingable toward each other so that the flat faces of their semi-circular sections may abut each other; a spring member arranged between said fingers for urging them apart; a slot on said second member; a latch having a clevis portion pivotally secured to said rectangular portion and having an end portion engageable in said slot for holding said fingers apart in a predetermined relationship; spring means for urging said latch into engagement with said slot; and means for releasing said latch.

11. A bowling attachment for an artificial arm, comprising an elongated fixed member having one of its ends secured in said arm and having its other end provided with a pair of relatively movable fingers, one of which is integral with said member and the other of which is pivotally mounted on said member, said fingers having abuttable faces substantially coinciding with a plane through the axis of rotation of the movable

finger, spring means between said fingers for urging them apart, a slot in a portion of the movable finger adjacent to its axis of rotation, a spring pressed latch engageable in said slot for holding said fingers in their spring separated positions, and a slot in said latch for receiving a latch releasing cable.

12. In combination, a bowling ball having a socket whose cross-section inwardly of the ball is larger than that juxtaposed its surface, thereby providing said socket with a lip, and an attachment for manipulating said ball when bowling, comprising an elongated member having one of its ends provided with a pair of relatively movable fingers, said fingers having enlarged end portions receivable in the enlarged portion of said socket and adapted to underlie said lip when spread apart, a spring operable upon said fingers for urging said fingers apart, and latch means for holding said fingers apart.

13. The combination as claimed in claim 12 wherein the said enlarged portions of the fingers include camming portions for facilitating entrance of the fingers into the ball socket.
